SELF-BALANCING DEVICE FOR TURBINES.

1,111,312.

Specification of Letters Patent. Patented Sept. 22, 1914.

Application filed July 26, 1913. Serial No. 781,362.

To all whom it may concern:

Be it known that I, FREDRIK LJUNGSTRÖM, a citizen of Sweden, residing at 2 Drottningholmsvägen, Stockholm, Sweden, 5 have invented certain new and useful Improvements in Self-Balancing Devices for Steam or Gas Turbines, of which the following is a specification.

For the purpose of balancing the axial 10 pressure of the steam in turbines, especially radial turbines, the steam is caused to enter into the space between the one turbine disk or a disk, connected therewith and the opposite wall of the casing, these surfaces being 15 provided with labyrinth-packings in the form of concentric rings and grooves, entering into each other, in order to minimize the quantity of balancing steam. The steam in this case is caused to pass in a wave-like 20 path beyond the ring edges. If however, the cross area of the steam path at the labyrinth ring edges is altered due to an axial displacement of the turbine disks, a sudden alteration of the steam pressure occurs, as 25 all the passages are simultaneously opened in the same degree. Hereby axial vibrations arise, which can be eliminated only with difficulty. To avoid this disadvantage the labyrinth packings, according to the 30 present invention, are constructed in such a way, that at the axial mutual displacement of the rings and grooves, all their passages will not be altered simultaneously, but the packings are successively opened or closed. 35 This is attained by the ring edges lying on a conical or step-formed line, that is to say, they have not all the same height, consequently a wedge shaped path is produced, presenting greater resistance for the steam, 40 and the expansion of the steam and the decrease of the tension of same will be greater.

Different embodiments of the invention are shown in longitudinal section in Figures 1, 2 and 3 of the accompanying drawing.

45 α indicates the turbine wheel or disk, carrying the blades d , and b indicates a stationary disk, arranged opposite the disk α . The disk α and b carry the concentric packing rings e , e^1 and e , of which e and e^1 are 50 shaped so as to act in opposite directions, as at the movement of the disk α to the right

the passages at e^1 are altered, while at the movement of the disk α to the left the passages at e are altered. According to the present invention the rings or ribs e and e^1 55 are now shaped in such a way, that all of them will not be brought into or out of action simultaneously, but at a movement of the disk α to the left the packing rings e are opened successively and at a movement 60 of said disk to the right the packing rings e^1 are similarly opened. In the embodiment shown this is attained by the packing rings e and e^1 having different height, as their edges lie on a conical surface, while 65 the edges of the rings e lie in the same plane.

Fig. 2 shows an embodiment, in which the height of the rings e is irregular, so that the edges thereof do not lie on a conical surface. The operation corresponds however 70 to that of the device according to Fig. 1.

According to Fig. 3 the rings e all have the same height, while the rings e are of different height.

Having thus fully described my invention, 75 what I claim as new, and desire to secure by Letters Patent, is:

1. In a steam turbine, a rotary member, a stationary member, and a plurality of packing ribs on said rotary member adapted 80 to coöperate with a plurality of grooves formed on said stationary member and to form therewith a steam passage of varying cross-section the packing ribs being of varying depth relatively to the grooves in the 85 stationary member.

2. In a steam turbine, a stationary member and a rotary member formed with a plurality of packing ribs adapted to engage in grooves formed on the opposing surface of 90 said stationary member and to form therewith a steam passage of a progressively varying cross-section the packing ribs being of varying depth relatively to the grooves in the stationary member. 95

3. A steam turbine comprising a stationary disk and a rotary disk having two series of annular ribs, coöoperating with grooves in said stationary disk to constitute two series of packing ribs and to form a passage for 100 the steam, one series of ribs being adapted to become successively opened upon the axial

displacement of the rotary disk in the one direction and the other series being adapted to become likewise opened successively upon the axial displacement of the rotary disk in 5 the opposite direction the packing ribs being of varying depth relatively to the grooves in the stationary disk.

In testimony whereof I have affixed my signature in presence of two witnesses.

FREDRIK LJUNGSTRÖM.
